UNITED STATES PATENT OFFICE.

FRANZ MARKERT, OF ALTWASSER, GERMANY, ASSIGNOR TO THE
CERAMIC TRANSFER CO., A CORPORATION OF NEW YORK.

DESIGN FOR A TRANSFER-SHEET.

No. 38,105.

Specification for Design.

Patented June 26, 1906.

Application filed May 2, 1906. Serial No. 314,903. Term of patent 3½ years.

To all whom it may concern:

Be it known that I, FRANZ MARKERT, a subject of the Emperor of Germany, residing at Altwasser, in the Province of Silesia, Germany, have invented a new, original, and ornamental Design for Transfer-Sheets, of which the following is a specification, reference being had to the accompanying drawing, forming part thereof.

The figure is a plan view of a transfer-

sheet for applying ornamentation to an article of china, porcelain, or earthenware, showing my new design.

I claim—

The ornamental design for a transfer-sheet as shown.

FRANZ MARKERT.
